(57) **CLAIM**

The ornamental design for a bus bar, as shown and described.

DESCRIPTION

FIG. 1 illustrates a perspective view of a bus bar system having a bus bar;

FIG. 2 illustrates a perspective view of the bus bar shown in FIG. 1;

FIG. 3 illustrates a plan view of one side of the bus bar shown in FIG. 2;

FIG. 4 illustrates a plan view of an opposite side of the bus bar shown in FIG. 2;

FIG. 5 illustrates an elevational view of one end of the bus bar shown in FIG. 2;

FIG. 6 illustrates an elevational view of an opposite end of the bus bar shown in FIG. 2;

FIG. 7 illustrates an elevational view of one edge of the bus bar shown in FIG. 2; and,

FIG. 8 illustrates an elevational view of an opposite edge of the bus bar shown in FIG. 2.

The broken lines illustrate portions of the bus bar system and bus bar that form no part of the claimed design.
